UNITED STATES PATENT OFFICE

2,254,018

COMBINATION FLUSH TANK VALVE AND
OVERFLOW PIPE

Carmine Polcari, Boston, Mass.

Application February 26, 1941, Serial No. 380,710

4 Claims.

(Cl. 4—60)

This invention relates to toilet flush tanks and more particularly the outlet valves thereof.

The primary object of this invention resides in the provision of a combined outlet valve and overflow pipe for toilet flush tanks.

Another object of this invention resides in the provision of a combined outlet valve and overflow pipe for toilet flush tanks which will not allow the water in the tank to leak therefrom.

A further object of this invention resides in the provision of a combined outlet valve and overflow pipe for toilet flush tanks adapted to be operated by the conventional means used in opening the outlet valves of such tanks.

A still further object of this invention resides in the particular construction of the valve.

Aside from the foregoing objects this invention resides in particular construction of the guide-yoke of the valve.

In addition to the aforesaid objects this invention resides in the particular construction of the valve operating link.

One of the salient features of this invention resides in the provision of a valve adapted to release the water from the tank in considerable volume.

With these and other objects in view this invention resides in certain novel features of construction and arrangement of elements to be hereinafter fully set forth in the specification, illustrated in the accompanying drawing and pointed out in the appended claims and, while this disclosure depicts my present conception of the invention, the right is reserved to resort to such changes in construction and arrangement of elements as come within the scope of the claims.

In the accompanying drawing forming a part of this application:

Fig. 1 is a sectional view of a portion of a toilet flush tank showing the combined valve and overflow pipe in full lines.

Fig. 2 is a sectional view thereof approximately on line 2—2 of Fig. 1.

Fig. 3 is a view similar to Fig. 1 on a reduced scale showing the valve in open position.

Fig. 4 is a detail perspective view of the valve-sleeve.

In the present illustration of this invention the letter F designates a portion of the conventional flush tank for toilets, the same having a hole H in its bottom for reception of a nipple 5 which is exteriorly threaded as at 6 to permit sealing of the same against leakage through the instrumentality of gaskets 7 and jam-nuts 8.

The upper end of the nipple is bevelled to form a valve-seat 9 against which a gasket 10, carried by a valve 11, is normally held closed by an expansion coil spring 12 having its upper end resting against an annular ring 13 supported by a skeleton guide-yoke 14 whose base 15 is threadedly secured on a threaded portion 16 of the nipple.

Threadedly secured to the lower end of the valve and retaining the aforesaid gasket 10 thereon is a valve-sleeve 17 which extends into the nipple and is provided with large ports 17', said valve-sleeve is provided with an upwardly extending fin 18 having an apertured head 19 to which is attached the lower ends 20 of a twisted wire link 21 adapted to be connected to the conventional valve operating lever, not shown, of the flush tank as by means of a hook 22 or the like.

Secured to that end of the valve opposite the valve-sleeve supporting end thereof, as by screw threads, is a tubular overflow pipe 23 in which the aforesaid fin extends for connection to the link, said tubular overflow pipe slidably passes through the ring of the skeleton guide-yoke and is surrounded by the aforesaid coil spring.

With the aforesaid elements disposed in operative position in a flush tank and the link 21 connected to the conventional valve operating lever thereof, operation of the latter in the usual manner will elevate the valve 11 against the spring 12 causing the ports 17' in the valve-sleeve to register with the interior of the tank and thereby permit the water therein to flow freely therefrom and, when the opening lever of the valve is released, the valve will be returned to closed position by the coil spring 12.

With this invention fully set forth it is manifest that a leak proof outlet valve for toilet flush tanks is provided and, through the instrumentality of the overflow pipe carried thereby guiding the valve, accurate seating of the valve is ensured.

Having thus described my invention what I claim and desire to protect by Letters Patent is:

1. The combination with a toilet flush tank and its valve operating lever, a nipple extending through and secured to the bottom of the tank and having exterior threads adjacent its upper end, a valve-seat formed on the upper end of the sleeve, a gasket resting on the valve-seat, a valve carrying the gasket at its lower end, a valve-sleeve secured at its upper end to the valve and extending into the nipple, said valve-sleeve having large ports adjacent its lower end, an elongated overflow pipe threadedly secured to the upper end of the valve, a skeleton guide-yoke

threadedly secured to the upper threaded portion of the nipple with its upper end surrounding the overflow pipe, an expansion coil spring surrounding the overflow pipe with its upper end bearing against the upper end of the skeleton guide-yoke and its lower end bearing against the upper end of the valve, an upwardly extending fin formed on the valve-sleeve disposed in the overflow pipe, an apertured head formed on the upper end of the fin, a twisted wire link having its lower ends spread and connected to the head of the fin, and a hook carried by the upper end of the link connected to the valve operating lever.

2. The combination with a toilet flush tank and its outlet valve operating lever, a vertically slidable outlet valve in the bottom of the tank, an apertured valve-sleeve carried by the valve and extending into the tank outlet, an overflow pipe carried by the valve and extending into the tank, a guide-yoke slidably receiving the overflow pipe, an expansion coil spring surrounding the overflow pipe disposed between the valve and guide-yoke and means connecting the valve to the valve operating lever of the tank.

3. A toilet flush tank valve comprising a nipple having a valve seat on its upper end, a valve including a gasket resting on the valve seat, an apertured valve-sleeve depending from the valve and extending into the nipple, an upwardly extending fin formed on the valve-sleeve, an apertured head formed on the fin, an overflow pipe extending from the upper end of the valve and surrounding the aforesaid fin, a skeleton guide-yoke secured to the nipple with its upper end

slidably receiving the overflow pipe, an expansion coil spring disposed around the overflow pipe between the upper end of the guide-yoke and valve and a link connected to the head of the fin and extending beyond the upper end of the overflow pipe.

4. The combination with a toilet flush tank and its valve operating lever, a nipple extending through and secured to the bottom of the tank and having exterior threads adjacent its upper end, a valve seat formed on the upper end of the sleeve, a gasket resting on the valve seat, a valve carrying the gasket at its lower end, a valve sleeve secured at its upper end to the valve and extending into the nipple, said valve sleeve having large ports adjacent its lower end, an elongated overflow pipe threadedly secured to the upper end of the valve, a skeleton guide yoke secured to the upper threaded portion of the nipple with its upper end surrounding the overflow pipe, an expansion coil spring surrounding the overflow pipe with its upper end bearing against the upper end of the skeleton guide yoke and its lower end bearing against the upper end of the valve, an upwardly extending fin formed on the valve sleeve disposed in the overflow pipe, a head formed on the upper end of the fin and having laterally spaced apertures therein, a flexible element having diverging arms connected at their free ends in said apertures of the head, and a hook carried by the upper end of the link connected to the valve operating lever.
